SPRAY FORMING SHOWER TUBE

Willard C. Stievater, Tonawanda, N. Y.

Application August 17, 1950, Serial No. 179,977

2 Claims. (Cl. 299—104)

1

My invention relates to shower tubes and more particularly to spray forming shower tubes.

The objects of my invention are to provide a simple, lightweight, durable and effective spray forming shower tube which is adaptable to various uses and which may be manufactured and sold at a low price; to provide a shower tube with a set of non-clogging discharge ports and a head spaced, formed and arranged with respect to the set of ports to produce a desired spray pattern, and to provide a shower tube with a plurality of sets of ports and heads, spaced, formed and arranged along the tube to produce spray patterns which intermingle and form a wall of spray suitable for an intended use.

In the drawing:

Figure 1 is an elevational view of a portion of a shower tube provided with one of my improved spray forming devices.

Figure 2 is a longitudinal sectional view taken on line 2—2 of Figure 1.

Figure 3 is a perspective view of a portable shower device in which the shower tube is provided with a spaced plurality of the spray forming devices, shown in Figures 1 and 2, and is bent to form an inverted U-shaped shower bath standard; and

Figure 4 is an elevational view of a portion of a shower tube modified to provide another form of spray pattern.

For the purpose of exemplifying the principles of my invention Figures 1 and 2 of the drawing show a supply tube 10 having its side wall provided with a pair of discharge holes 11 which are spaced apart and located in a plane aligned with the axis of the tube. A head 12, formed with a frusto-conical shaped surface 13, is secured to the tube with the surface 13 spaced from and overlying the holes 11. The head 12, for the sake of simplicity and low cost is preferably formed of a rust proof standard flat-head machine screw which may be readily screwed in a tapped hole 14 formed in the tube 10 between the holes 11 or, if it is desired to eliminate the operation of tapping the hole, a so-called self-tapping screw may be used. In either case the head is screwed tightly against the tube and does not require any locking devices to prevent its displacement.

The included angle of the frusto-conical surface of a standard flat head machine screw is usually 82° and provides a head satisfactory for many uses, however, it is contemplated that heads having different included angles may be used for other uses.

2

It will be apparent from the form, arrangement and relative sizes of the holes 11 and the head 12 that streams of fluid forced through the pair of holes 11 will be deflected by the frusto-conical surface 13 of the head 12 and, somewhat as is indicated by broken lines in the drawing, will form a pair of conically shaped segments of spray "S" the medial centers of which lie in a plane parallel to the tube. The angle and curvature of the surface 13 and the location of the holes 11 is such that the medial portion of each spray is more concentrated or dense than its sides, and the sprays combine to provide a spray pattern of greater extent in the plane of the tube than in a plane transverse thereto. A shower having a spray pattern of this type requires less fluid than a spray pattern of uniform density and greater transverse extent and is well adapted to certain uses.

In the event conservation of fluid is of less importance than providing a spray pattern of greater transverse extent and more or less uniform density the tube 10 may be provided with additional pairs of spaced fluid discharge holes, as indicated in Figure 4 by the numeral 11; so that sprays "S'" are formed and intermingle with the sprays "S" to provide the desired spray pattern.

The holes 11 are of small diameter but since their function is to direct streams of fluid against the head 12 which deflects and converts the streams into spray, they are not extremely small and are not readily clogged by dirt and other foreign substances that would block smaller holes.

The shower tube 10 of the present invention among its many possible uses, is well adapted for use in an inexpensive, light and portable shower device which, when connected to a source of water under pressure, serves as an outdoor shower for persons wishing to use its spray for cooling themselves and other purposes, and the device is readily movable from place to place to also utilize its spray for watering different portions of an area, for example, a lawn.

In Figure 3 the numeral 15 generally designates a form of shower device which has proven satisfactory for the above described purposes, and in which a length of the tube 10, in a plane parallel to its axis, is provided with spaced sets of the spray forming devices shown in Figures 1 and 2. The tube 10 is then bent to form an inverted U-shaped standard 15 in which the axis of the head and the holes of each set of spray forming devices are aligned and directed toward the center of the standard, so that the

sprays "S" are directed toward the center of the standard and intermingling, thereby forming a wall of spray "W" in the standard.

The standard 15 may be supported in its upright position by any suitable form of base, however, in order to lower costs and weight, I prefer to utilize the section of tubing remaining after the standard 15 is formed from a stock length of tubing to form the four supporting feet 16 for the standard. The feet 16 are secured in the opposite ends of the heads of a pair of T-fittings 17 one of which is secured to each end of the standard with its head in a plane transverse to the plane of the standard so that the four feet 16 provide a light and stable base for the standard.

The outer end of one of the feet 16 is provided with a coupling 18 for detachably connecting the device 15 to a source of water pressure, e. g. a garden hose 19. Water entering the foot, provided with the coupling 18, passes through the associated fitting 17 and enters one end of the standard and to prevent water from flowing through the other feet suitable plugs (not shown) are provided.

The size and extent of the spray may be varied to suit one's needs and desires by simply opening or closing a suitable flow controlling valve (not shown).

Having now illustrated and described my invention, I wish it to be understood that my invention is not to be limited to the specific form and arrangement of parts shown and described or specifically covered by my claims:

I claim:

1. A water spraying device comprising a section of tubing formed with a closed end and an open end adapted for connection to a source of water under pressure, said tubing being formed with a plurality of spaced radially disposed

screw-receiving through holes having their axes in a common plane longitudinally of the tubing and being formed with a plurality of small water discharge through holes equally spaced from each screw receiving hole and having their axes parallel to the axis of the associated screw receiving hole; and a screw screwed into each screw receiving hole, each of said screws serving to prevent flow of water through its screw receiving hole and being formed with a frusto-conically shaped head portion which overlies the associated plurality of discharge holes in outwardly diverging spaced relation and which serves to deflect and thereby convert the parallel streams of water emerging from the associated plurality of discharge holes into water spray suitable for intended uses of the device.

2. A water spraying device as set forth in claim 1 wherein the tubing is bent intermediate its closed and open end so that it forms an inverted U-shaped arch and the axes of all of the screws and discharge holes are directed inwardly, thereby providing a wall of inwardly directed spray in the arch, and the arch is provided with means for maintaining it in a fixed upright position.

WILLARD C. STIEVATER.
